UNITED STATES PATENT OFFICE.

PETER SJOSTROM AND AUGUST MOBERG, OF MAPLEWOOD, MASSACHUSETTS.

CHANNELING-TOOL.

1,171,985.

Specification of Letters Patent.

Patented Feb. 15, 1916.

Application filed May 20, 1915. Serial No. 29,423.

To all whom it may concern:

Be it known that we, PETER SJOSTROM, a subject of the King of Sweden, and AUGUST MOBERG, a citizen of the United States of 5 America, residents of Maplewood, in the county of Middlesex and Commonwealth of Massachusetts, have invented certain new and useful Improvements in Channeling-Tools, of which the following is a specification.

This invention relates to hand tools for cutting channels in soles of boots and shoes and is especially adapted for use in repair 10 shops.

The object of the present invention is to 15 provide a tool of this class in which various shaped cutting knives may be used and in which the knife may be readily adjusted either longitudinally or about its axis and then clamped in such adjusted position.

Another object of the invention is the provision of a tool of this character in which the cutting head is pivoted to the operating handle so that the tool may follow the sole and cut a uniform depth of channel regardless of the angular position of the handle 20 during the cutting operation.

The invention consists of certain novel features of construction and arrangement of parts which will be fully understood by reference to the description of the drawings 25 and to the claims hereinafter given.

Of the drawings, Figure 1 represents a rear elevation of a tool embodying the principles of the present invention. Fig. 2 represents a side elevation of the same. Fig. 3 represents a front elevation of the same with the cutting head thereof in section. Fig. 4 represents a longitudinal section of the same the cutting plane being on line 4—4 on Fig. 1. Fig. 5 represents an inverted plan 35 of the same. Fig. 6 represents a sectional elevation of a portion of the same the cutting plane being on line 6—6 on Fig. 3. Fig. 7 represents an elevation of the cutting tool. Fig. 8 represents a plan view of the same, and Fig. 9 represents an end view of the same.

Similar characters designate like parts

throughout the several figures of the drawings.

In the drawings 10 is a handle having secured thereto a flat sided shank 11 provided with a transverse pivot pin 12 the ends of which extend beyond the side faces of said shank and are positioned in a bifurcated cutter head 13, the arms of which straddle said shank 11, as shown in Fig. 4.

The cutter head 13 is provided with a downwardly extending flange 14 adapted to bear against the edge of a shoe sole during 60 the cutting operation.

On the flanged side of the cutter head is a split boss 15 having its outer end cone-shaped while the periphery thereof is threaded, as indicated at 16. Through the 65 boss 15 is a cylindrical hole 17 in which is mounted the cylindrical shank 18 of the cutting knife 19. The cutting edge of the knife 19 may be of any desired shape according to the work to be done.

In the embodiment shown in the drawings the knife 19 is provided with a cutting edge 20 approximately perpendicular to the inner face of the flange 14 and with another cutting edge 21 substantially parallel with said 75 inner face of the flange 14, said cutting edges 20—21 coacting to cut an L-shaped channel in the face of a shoe sole.

The cutting edge 21 may be adjusted toward and from the flange 14 thereby determining the distance from the edge of a sole 80 that the channel will be cut therein.

The cutting edge 20 may be adjusted to cut different depths of channels by rotating the shank 18 about its axis.

When the necessary adjustments of the knife 19 have been made it is locked in adjusted position by means of the nut 22 which is provided with a cone-shaped inner wall 23 adapted to engage with the conical end of 90 the split hub or boss 15 and force the various sections thereof into gripping contact with the shank 18 of said knife.

The outer end of the shank 18 is provided with a plurality of perforations 24 in either 95 of which a pin or other device may be in-

serted in order to readily adjust the cutting knife when the nut 22 has been moved sufficiently to release the gripping contact of the sections of the boss 15 thereon.

- 5 It will be observed by an inspection of the drawings that the cutting edge 21 is approximately parallel with the pivot pin 12 and slightly in advance thereof during the cutting operation.
- 10 By pivoting the cutter head 13 to the handle 10 the knife 19 is permitted to travel through the material always at the same distance from the face thereof regardless of the angle that the handle 10 may assume as the 15 operator moves the tool over the sole with the flange in contact with the edge thereof.

The depth of the channel is determined by the distance the cutting edge 20 is located beneath the bearing portion 25 of the head 20 13, the portion 25 being moved over the sole in contact with its upper face during the channel cutting operation.

This makes a very convenient tool for operators in repair shops, it being simple in 25 construction and very effective in operation. It is capable of all necessary adjustments for various depths of channels at various distances from the edge of the shoe sole, and the knife shown may be quickly removed and a different style or shape of knife 30 substituted therefor when it is desired to cut different forms of channel.

It is believed that the operation and many 35 advantages of a tool of this construction will be fully understood without further description.

Having described our invention, we claim—

1. In a device of the class described, the 40 combination of a handle; a member connected to one end thereof by a transverse pivot and having a flange formed integral therewith adapted to engage the edge of a sole; and a knife carried by said member 45 with a cutting edge approximately perpendicular to the inner face of said flange and opposite thereto.

2. In a device of the class described, the 50 combination of a handle; a member connected to one end thereof by a transverse pivot and having a flange adapted to engage the edge of a sole; a knife member carried by said member with a cutting edge at one end approximately perpendicular to the inner 55 face of said flange and adjustable endwise toward and from said flange; and means for locking said knife member in adjusted position.

3. In a device of the class described, the 60 combination of a handle; a member connected to one end thereof by a transverse pivot and having a flange adapted to engage the edge of a sole; a knife having a shank

mounted in said member and provided with a cutting edge approximately perpendicular 65 to the inner face of said flange, said knife being adjustable about the axis of said shank; and means for locking said knife in adjusted position.

4. In a device of the class described, the 70 combination of a handle; a pin perpendicular to the axis thereof; a bifurcated member mounted on said pin and having a sole-edge-engaging flange; a knife carried by said member with a cutting edge extending 75 across the forked end thereof; and means whereby the knife may be adjusted toward and from said flange and locked in adjusted position.

5. In a device of the class described, the 80 combination of a handle; a pin perpendicular to the axis thereof; a bifurcated member mounted on said pin and having a sole-edge-engaging flange; a cylindrical member carried by said bifurcated member and having 85 at one end thereof a knife with a cutting edge extending across the forked end of said bifurcated member; and means whereby said cylindrical member may be adjusted about its own axis, may be moved endwise, and 90 may be locked in adjusted position.

6. In a device of the class described, the combination of a handle; a member connected to the end thereof by a transverse pivot and having a sole-edge-engaging 95 flange; a hub on the outer face of said flange; a knife mounted in said hub with a cutting edge extending inwardly from the inner face of said flange; and means for locking said knife in adjusted position 100 within said hub.

7. In a device of the class described, the combination of a handle; a member connected to the end thereof by a transverse pivot and having a sole-edge-engaging 105 flange; a hub on the outer face of said flange; a knife with a cylindrical shank mounted in said hub with a cutting edge extending inwardly from the inner face of said flange; and means for locking the shank 110 of said knife in adjusted position within said hub.

8. In a device of the class described, the combination of a handle; a member connected to the end thereof by a transverse 115 pivot and having a sole-edge-engaging flange; a split threaded hub on the outer face of said flange and provided with a tapered end; a knife with a cylindrical shank mounted in said hub with a cutting 120 edge extending inwardly from the inner face of said flange; and a nut threaded to said hub and provided with a tapered bore adapted to engage the end of said hub and force it into clamping engagement with the 125 shank of said knife.

9. In a device of the class described, the combination of a handle; a member connected to the end thereof by a transverse pivot and having a sole-edge-engaging flange; a hub on the outer face of said flange; a knife with a cylindrical shank mounted in said hub with a cutting edge extending inwardly from the inner face of said flange; means whereby said shank may be adjusted about its axis; and means for locking the shank

10 of said knife in adjusted position within said hub.

Signed by us at 4 Post Office Sq., Boston, Mass., this 15th day of May, 1915.

PETER SJOSTROM.
AUGUST MOBERG.
